UNITED STATES PATENT OFFICE.

FRANK M. SLOUGH, OF ELYRIA, OHIO, ASSIGNEE TO THE DEAN ELECTRIC COMPANY, OF ELYRIA, OHIO, A CORPORATION OF OHIO.

ELECTRICAL SIGNALING SYSTEM.

982,505.

Specification of Letters Patent. Patented Aug. 31, 1903.

Application filed July 16, 1906. Serial No. 325,553.

To all whom it may concern:

Be it known that I, FRANK M. SLOUGH, a citizen of the United States, residing at Elyria, in the county of Lorain and State 5 of Ohio, have invented certain new and useful Improvements in Electrical Signaling Systems, of which the following is a specification, reference being had therein to the accompanying drawing.

10 This invention relates to electrical signaling systems and especially to what are called harmonic signaling systems.

It is particularly applicable to signaling over telephone lines for the purpose of selecting one party alone out of several on the same line.

15 The object of the invention is to perfect and simplify apparatus of this class, reducing the amount of apparatus required by 20 employing pole changers instead of generators and using a minimum number of contacts thereon.

Further objects will appear hereinafter.

25 Heretofore it has been found difficult to construct reeds or armatures for harmonic vibrators or pole changers which would vibrate at a constant periodicity, especially after they have operated for a considerable length of time. It is exceedingly desirable, 30 therefore, to eliminate all chance for mechanical change in the reed and to this end the spring and armature are all made in one piece according to the present invention. Moreover, with reeds vibrating at a low rate 35 of speed there is, of course, very little trouble experienced in maintaining a constant rate. These operating reeds are driven by motor magnets deriving their current from contact devices controlled by the slow reed, and they

40 can be readily synchronized, or more accurately tuned, by means of an extra winding placed on each motor magnet and controlled in the vibration of its own reed. Ordinarily I prefer to use the slowest of a 45 set of vibrating reeds as the master or controlling reed, so that while each of the set governs its own synchronizing winding, there is always a controlling grasp extended by the master reed and acting at intervals 50 on each of the other reeds to prevent departure by either acceleration or retardation from the desired rate.

Instead of employing one of a set of working reeds for a master reed, I may provide

a separate and distinct mechanism for this 55 purpose comprising an especially constructed magnet and reed, whose design is such that a very constant rate of vibration will be maintained.

In the ordinary four-frequency harmonic 60 signaling system, as employed by the Dean Electric Company, the frequencies employed are 16, 33, 50 and 66, respectively. Of these I select the 16-cycle vibrator, being the slowest, as the standard or master vibrator. 65 Each of the other vibrators has two windings, one in series with a contact controlled in its own movement and the other depending upon the master vibrator. The connections are such that these second windings 70 on the three higher vibrators receive impulses or currents from the vibration of the 16-cycle vibrator. In other words, the 33-cycle vibrator will receive an extra impulse every two vibrations, the 50-cycle vibrator 75 every three vibrations, and the 66-cycle vibrator every four vibrations. If one of these armatures had a tendency to speed up, these extra pulsations would retard its movement and bring it back to its normal period. Conversely, if an armature had a tendency to retardation, these extra pulsations would tend to accelerate it and bring it up to normal speed. The synchronizing windings, as 80 they may be called, on the three vibrators 85 are placed in multiple by preference, but when properly constructed, they can of course be operated in series.

The invention is illustrated in the accompanying drawings in which—

90 Figure 1 is a diagram of a harmonic vibrator set consisting of four units, arranged so as to make 16, 33, 50 and 66 cycles of movement per second respectively, the low speed vibrator on the left furnishing synchronizing impulses in the other three. Fig. 95 2 is a similar diagram showing four vibrators, with a separate master vibrator supplying the synchronizing impulses.

Referring to these figures, I may state at 100 the outset that the apparatus and circuits illustrated are designed especially for use in telephone systems.

In Fig. 1 P represents the calling plug of an operator's pair, which is adapted to co-operate with the jack J of a telephone line 1—2 serving four stations A, A', A'', and A''. The tip and sleeve conductors 3—4 of the

cord lead from the tip and sleeve of the plug respectively, to the ringing key K, which is normally closed so as to complete the talking circuit through the conductors 5 and 6 to the 5 other plug of the pair, which is not illustrated. This portion of the diagram is not complete as to a telephone system, but is meant to suggest all the necessary apparatus and circuits required to constitute an operative system. The ringing key when operated 10 has its springs 7 and 8 spread apart so as to break the cord circuit and prevent back ringing, spring 8 being grounded at the same time. In order to supply any one of a number 15 of frequencies of calling current to the tip conductor 3 and thence to the line, selective keys k , k' , k^2 and k^3 are provided of a type well known and not requiring any description. The ringing leads from these 20 keys are numbered 9, 10, 11 and 12, respectively, each terminating at the secondary of the transformer which is grounded on the other side. These transformers are associated with the four pole changers V, V' , 25 V^2 and V^3 . Each of these has a vibrating member v , controlled by a motor magnet M with two windings, except the first magnet which only has one winding. The primary winding of each transformer is connected on 30 one side to the contacts 13—14, and on the other side to the contacts 15—16. Between the contacts 13 and 15 a spring arm 17 vibrates and between the contacts 14 and 16 a similar arm 18 vibrates. Both of these arms 35 are carried on the vibrator v , which also carries a stub spring 19 which makes and breaks with the contact 20 of the motor magnet circuit. The spring 17 is insulated from the vibrator, but the other two springs, 18 40 and 19, are in metallic contact therewith, and are thereby connected to ground.

From the main battery B a feed wire 21 extends to all the pole changers, with individual branches 22, 23, 24 and 25 extending 45 to the several motor magnets. In the pole changer V the wire 22 passes to the magnet M, supplying current to both windings, which are connected on the other side through the wire 26 to the contact 20. This 50 pole changer V has a normal periodicity of 16, and as I have stated, this slow speed renders it comparatively easy to maintain a constant rate of vibration. The other three pole changers, however, require synchronizing, and the slow speed apparatus V is employed for this purpose in the following 55 manner: taking the pole changer V' for example, the magnet M has two windings, viz., a motor winding m and a synchronizing winding m' . The circuit of the motor winding is through wire 23 to the magnet and then by wire 27 to the contact 28 co-operating 60 with the stub spring 29 on the vibrator v and thence to ground. The circuit of the synchronizing winding, however, is traced

through the feed wire 23 to the magnet and then by branch 30 to the main synchronizing wire 31 and so to the contact 20 and spring 19 of the master vibrator V, which supplies the ground to complete the circuit through 70 its vibrating arm v . The arrangement of the other pole changers V^2 and V^3 is the same as that of V', hence they will need no separate description and I may pass at once to the statement of operation.

Assuming the circuit of the main battery B to be closed, from the bus b on to the feed wire 21, the vibrators v of the pole changers will all start up and oscillate continuously. In oscillating, they move the springs 17 and 18 back and forth between the respective pairs of primary contacts, thereby producing reversals of current in the primary windings of their respective transformers, due to the shifting of the main battery B from contact 85 13 to contact 15 and back again, while ground is alternately placed on the contacts 16 and 14. The transformers are thus prepared to deliver alternating currents of the proper frequencies through the wires 9, 10, 90 11 and 12 when their respective keys k , k' , k^2 and k^3 are manipulated.

As before stated, the vibration of the arm v in the pole changer V is taken as the standard, this arm being adjusted for constant 95 vibration. Its motor magnet works directly on the following simple circuit: B, 21, 22, M, 26, 20, 19, v , and ground. As the contacts 19 and 20 make and break the magnet oscillates the arm back and forth. Each of 100 the other pole changers works on an individual motor circuit similar to the following: B, 21, 23, m , 27, 28, v and ground. Each of the others also has a synchronizing circuit similar to the following: B, 21, 23, m' , 30, 31, 105 20, 19, v and ground. Obviously, a pulsation of current will be sent over this synchronizing circuit once for each vibration of the arm v of the master pole changer V. Since 110 the rates of vibration of the other pole changers are approximate multiples of that of the pole changer V, it follows that each of them will vibrate its arm v a certain number of times for each single vibration of the master pole changer arm. In the case of the 115 pole changer V' which has a frequency of 33, the winding m' will receive a pulsation of current through the branch 30 once in every 120 two vibrations of its arm v . In the case of the pole changer V^2 , these synchronizing impulses will be received once in three vibrations of its arms; and in the case of the pole changer V^3 , the synchronizing impulse will be received once in four vibrations of its arm. The effect of these synchronizing 125 impulses is to keep the rates of vibration approximately constant, taking the low speed vibrator as a standard. If one of the arms has a tendency to slow down a little, it will obviously be pulled up each time the 130

synchronizing impulse comes, while one that has a tendency to speed up will be pulled down.

Fig. 2 is a skeleton diagram of a modified layout for a separate master vibrator or synchronizer. In this figure the pole changers and their non-essential elements are omitted, the vibrators v and the motor magnets M being shown naked by themselves. Each motor magnet has its initial or individual motor winding m , as before, and each also has a synchronizing winding m' , the circuit being substantially the same as already traced with the difference that all four pole changers are here shown with double windings. The synchronizing wire 31 in this case passes to the contact 20 of an arm v_x in a master vibrator set V_x , having a motor magnet M_x . This motor magnet like all the others derives its motive current from the main battery wire 21, and is solidly attached to a heavy frame v_x' , which is grounded. It will be observed that the vibrator v_x has no pole changing arms or contacts and its mechanism throughout is exceedingly simple. This simplicity enables me to construct the device with great precision so as to make it very accurate in its operation. The arm, supporting spring, and armature, are all made in one piece and the device is suitably proportioned throughout so as to be accurately tuned to the master frequency for synchronizing purposes.

Thus it will be seen that I have provided a means for causing synchronous operation of a plurality of pole changers and that such pole changers may be considered to constitute a plurality of current producing means each adapted to supply current of definite characteristics to operate signaling apparatus designed to respond thereto.

I am aware that the system and apparatus I have thus described may be varied in many matters of detail without departing from the spirit of my invention, the underlying characteristic feature of which is the production of synchronizing impulses which are fed to the vibrating mechanisms at recurring intervals. My claims, therefore, are to be given a broad reading.

Having thus described my invention, what I claim and desire to secure by Letters Patent is:

1. In an electrical signaling system, mechanism for producing a periodic signaling current of definite frequency, a second mechanism for producing a second periodic signaling current of definite frequency and means whereby the pulsations of signaling current produced by such second mechanism tend to maintain constant the frequency of the signaling current produced by such first mechanism.

2. In an electrical signaling system, means for producing a periodic signaling current,

a separate synchronizer therefor, a common source of electric energy and means whereby the operation of such synchronizer tends to maintain constant the frequency of such signaling current.

3. In an electrical signaling system, a plurality of means for producing periodic signaling currents, a common synchronizing device or speed regulator therefor and means whereby the operation of such synchronizer tends to maintain constant the frequency of such signaling currents.

4. In an electrical system, a plurality of means for producing periodic currents of different frequencies, a common synchronizing device for such current producing means and means whereby the operation of such synchronizer tends to maintain constant the frequency of such signaling currents.

5. In an electrical signaling system, a plurality of means for producing periodic signaling currents, each of such means including a motor mechanism and a separate synchronizing mechanism, a common synchronizer and means whereby the operation of such common synchronizer operates all of such synchronizing mechanisms and tends to maintain constant the frequency of such signaling currents.

6. In an electrical signaling system, a plurality of means for producing signaling currents, each of such means having an individual motor magnet and an auxiliary synchronizing magnet, each of such motor magnets tending by its operation to cause an approximately constant rate of movement, a common synchronizer and means whereby the operation of such synchronizer tends to maintain constant the rate of movement of each of such signal current producing means.

7. In an electrical system, a plurality of means for producing signaling currents adapted to be operated at approximately constant speeds, a regulating magnet for each of such current producing means, a common mechanism for producing synchronizing current and means whereby such synchronizing current actuates such regulating magnets and thereby tends to maintain constant the speeds of such current producing means.

8. In an electrical system, a plurality of current producing means individually driven at normally constant but different speeds, a common synchronizing device therefor and means for communicating synchronizing impulses from such synchronizing device to such current producing means, the rate of such impulses and the rates of speed of such current producing means being multiples of one another.

9. In an electrical system, a plurality of current producing means individually driven at normally constant but different speeds, a common synchronizing device therefor and

means for communicating synchronizing impulses from such synchronizing device to such current producing means.

10. In an electrical system, a plurality of current producing means actuated by periodic current at approximately constant but different speeds, a common synchronizing device therefor, means for communicating synchronizing impulses from such synchronizing device to such current producing means at pre-determined intervals, the rates of speed of such current producing means being multiples of the rate of such synchronizing intervals.

15. 11. In an electrical system, a current producing means adapted to be operated by periodic current, a synchronizing device and means for communicating synchronizing impulses of a frequency lower than the normal frequency of such current producing means from such synchronizing device to such current producing means whereby the frequency of such current producing means is maintained practically normal.

20. 12. In an electrical signaling system, a pole changer, an individual motor magnet therefor, a synchronizing magnet, and means to supply the latter with current impulses at recurring intervals, substantially as described.

25. 13. In an electrical signaling system, a plurality of pole changers having individual motor magnets and auxiliary synchronizing magnets, together with a common synchronizer connected to said auxiliary magnets, substantially as described.

30. 14. In an electrical signaling system, a plurality of pole changers tuned to work at distinctive frequencies, and a common synchronizer supplying current thereto for synchronizing purposes at a frequency not exceeding that of the slowest of the pole changers, substantially as described.

35. 15. In an electrical signaling system, a plurality of working pole changers for supplying signaling current at diverse frequencies, and a regulator or synchronizer common to all of said pole changers, the arrangement being such that the normal periods of the pole changers are approximately even multiples of the synchronizer period, substantially as described.

40. 16. In an electrical signaling system, a plurality of pole changers working at differ-

ent frequencies, a motor magnet for each pole changer and circuit controlling means for said magnet periodically operated by its own pole changer, an auxiliary magnet for each pole changer, and a common vibrator supplying periodic synchronizing impulses to said auxiliary magnets, substantially as described.

45. 17. In an electrical signaling system, a plurality of pole changers operating at different frequencies, a tuned vibrating arm for each pole changer, a motor magnet for each arm having its circuit governed thereby, an auxiliary motor magnet for each arm, a common circuit for all of said auxiliary magnets, and a master vibrator adjusted to have a constant rate of vibration, adapted to supply current impulses to the circuit of the auxiliary magnets at recurring intervals for regulating purposes, substantially as described.

50. 18. In a telephone exchange system, an operator's cord circuit and selective ringing key, in combination with a plurality of pole changers connected to said key, an individual motor magnet for each pole changer, auxiliary magnets for the pole changers, and a common synchronizing device governing the auxiliary magnets, substantially as described.

55. 19. In a telephone exchange system, subscribers' lines, one or more of said lines having a plurality of stations upon it, tuned harmonic ringers at said stations, connective apparatus for interconnecting the lines, a selective signaling apparatus comprising a plurality of individually driven harmonic current producing mechanisms for producing current at suitable frequencies to actuate the ringers at the sub-stations, together with synchronizing means common to said harmonic mechanisms.

60. 20. In a telephone exchange system, an operator's harmonic signaling apparatus comprising a plurality of individually driven harmonic current producing means, together with a common synchronizer operated at constant speed.

In testimony whereof I affix my signature in presence of two witnesses.

FRANK M. SLOUGH.
